UNITED STATES PATENT OFFICE.

ROBERT JOHN FOSTER AND HONORE LAUZON, OF MONTREAL, QUEBEC,
CANADA, ASSIGNORS TO MERGENTHALER LINOTYPE COMPANY, A COR-
PORATION OF NEW YORK.

LINOTYPE-MACHINE.

No. 845,227.

Specification of Letters Patent.

Patented Feb. 26, 1907.

Application filed February 18, 1905. Serial No. 348,358.

To all whom it may concern:

Be it known that we, ROBERT JOHN FOSTER and HONORE LAUZON, both of the city of Montreal, Province of Quebec, Canada, have invented certain new and useful Improvements in Indenting Mechanism for Linotype-Machines; and we do hereby declare that the following is a full, clear, and exact description of the same, reference being had to the accompanying drawings, forming a part hereof:

In typographic printing it is frequently necessary to leave a blank or unprinted space at one or both ends of a line. This setting of the characters inward away from the margin or end of the line is technically known as "indenting," and in the art of type composition the same term is used to indicate the corresponding arrangement of the type characters in a composed line with quads or blanks at the end or ends of the line beyond the type characters. When the blanks occur at the rear end of the line and are of great length, the foregoing operation is frequently termed "quadding out."

In linotype-machines the characters to print a line are formed in the edge of a continuous slug or Linotype having a length equal to the width of the entire page or column of print. The slugs are cast in a slotted mold and the characters formed upon them by a composed line of matrices confined momentarily against the mold by two opposing jaws.

The aim of our invention is to adapt the machine to automatically indent the characters on the slug at either or both ends to any required extent, and this without the employment of quads or blank matrices to fill out the composed line. To this end we combine with the mold and the usual matrices two sliding jaws, which serve to confine the matrix-line, as usual, and also to cover and close any portion of the mold which may extend to the right or left beyond the presented line of matrices in order that the jaws may form corresponding blank surfaces on the slugs beyond the type characters. With these jaws we combine means whereby their positions in relation to each other and to the mold may be controlled and their movements automatically effected in order to locate the matrix-line in proper relation to the mold.

We have shown our invention incorporated

in a Mergenthaler linotype-machine of the present commercial form, and it should be understood that all parts of the machine which are not shown in the drawings may be of the ordinary or any other suitable construction. The drawings are limited to those parts immediately associated with the invention.

Figure 1 is a top plan view showing a mold, the matrix-confining jaws, and our devices for controlling and operating the latter. Fig. 2 is a vertical section on the line 2 2, Fig. 1. Fig. 3 is a side elevation of the parts shown in Fig. 1 looking from the left, portions being shown in section. Fig. 4 is a section on the line 4 4, Fig. 1. Figs. 5 and 6 are plan views of the index-plates which receive the jaw-controlling pins. Fig. 7 is a front elevation illustrating the relation of the mold, matrices, and confining-jaws. Fig. 8 is a perspective view showing slugs with indented matter as produced by our mechanism.

Referring first to the slugs, which it is the purpose of our invention to produce, attention is directed to Fig. 9, in which X represents a linotype-slug having on the forward edge the type characters x, located at the left end, with a blank space x' at the right. X' represents a slug with the type characters at the right and the blank surface x' at the left. X² represents the slug with the type characters x at the center and blank surfaces x' at the two ends.

It will be observed that the lines of type characters on the respective slugs are of equal length, but shorter than the slugs and differently located thereon.

In the portion of the machine provided with our improvements it is only necessary to compose a line of those matrices which represent type characters, as the blank surfaces are produced by the jaws of the machine. This avoids the time and labor ordinarily required in composing the lines with quads to fill out beyond the type characters. As soon as the operator has designated the type characters the line is sent forward and he proceeds with the composition of the next line.

Referring now to Figs. 1, 2, and 3, A represents a front portion of the main frame, commonly known as the "vise-frame," and b and c are the two opposed horizontally-movable jaws arranged to slide in the vise-

frame for the purpose of confining the composed line of matrices between their inner ends in the casting position before the mold. *a* represents the usual mold, having a slot 5 therethrough from front to back of the dimensions of the required slug. During the casting action it stands in a horizontal position directly opposite the jaws *b* and *c*, which latter are adapted to cover and close any portion of the mold which may not be closed by the matrices. The mold is mounted in a vertical intermittently-rotated wheel or disk *a'*, which is movable forward and backward in order to first seat the face of the mold tightly 10 against the matrices seated between the jaws *b* and *c* and to thereafter retract the mold and the contained slug. So far as described these parts may all be constructed and arranged to operate as in the commercial 15 type-machines of the present day. Our devices are designed to control the movements and the operative positions of the jaws *b* and *c* in order to confine the matrix-line, whatever its length, between the jaws, and also to 20 determine the position of the matrix-line in relation to the mold.

To the right-hand jaw *c* we attach rigidly a controlling-bar *e*, extended horizontally through the frame to one side and provided 25 at its outer end with a toothed rack *d*, engaging a sectional pinion *m*, by means of which the rod may be caused to move the jaw *c* forward and backward lengthwise of the mold.

The bar *e* carries a rigid block *k*, through 30 which a longitudinally-adjustable rod 10 is extended in position to set against and support the outer end of the jaw *b*. It will be observed that the bar *e* and the rod 10 form 40 a rigid connection or coupling between the two jaws *b* and *c*, permitting them both to be moved endwise simultaneously in relation to the mold, so that the matrix-line confined between the jaws may be seated against the 45 mold at any desired point in its length.

The rod 10 (see Figs. 1 and 4) is provided on the upper side with a series of holes 2 to receive a stud 4 on the under side of the block *k*, the engagement being maintained 50 by a spring 6, carried by the block. By canting or tipping the rod it may be disengaged from the stud, so as to admit of its being moved endwise and reengaged in a new position. This longitudinal adjustment of 55 the rod admits of the distance between the two jaws being varied according to the length of the matrix-lines to be employed.

In order to cause the automatic endwise movement of the jaws and to control their 60 operative positions as the character and extent of the indentation may require, we provide the following parts: In the vise-frame or in a rigid plate *g* therein over the jaw *c* we form a series of holes adapted to receive a 65 stop-pin *j*. The jaw *c* is formed, as shown in

Fig. 2, with a lip *c'* at its outer or right end in such manner that the pin *j* may be seated either to the left of this lip in order to limit the motion of the jaw to the left or on the right of the lip to limit the movement of the 70 jaw to the right. The point at which the movement of the jaw will be arrested will be determined by the location of the pin in one or another of the holes. Over the jaw *b* we provide the vise-frame with a second series of 75 holes similar to those above described to receive a stop-pin *i*, by which the movement of the jaw *b* backward to the left may be arrested at any desired point.

It will be remembered that the bar *e* for 80 moving the jaws is connected with an actuating-pinion *m*. This pinion is provided with a crank-arm from which a connecting-rod *s s'* is extended rearward to a lever *n*, pivoted to the main frame.

A spring *v*, connecting the lever *n* with the main frame, urges the rod *s* constantly forward, and through the intermediate connection tends to move the two jaws *b* and *c* to the right, so that they will present the line of 90 matrices at the right-hand end of the mold, so that the indentation, if any, will occur at the left end of the slug in that part of the mold which is for the time being covered and closed by the jaw *b*.

The lever *n* carries a roller bearing on a vertical cam *o*, secured to the main cam-shaft *p* of the machine. This cam acting through the intermediate parts pulls the rod *s* rearward in opposition to the spring *v*, thereby causing the rod *e* and the jaws to move to the left, so as to carry the line of 100 matrices toward the left end of the mold until their advance is arrested by the contact of jaw *b* with the stop-pin *i*.

As the jaw has a variable movement, while the cam gives an invariable movement to the rod *s*, it is necessary to provide a yielding connection between the cam and the pinion in order that the cam and lever may continue 110 their motion after the jaw is arrested. For this purpose we connect the rods *s* and *s'* by springs, as shown in Figs. 3 and 5. The rod *s* is provided with a fixed collar 7, secured in one end of the spring *t*, which is in turn secured at the opposite end rigidly to a sleeve 8. This sleeve 8 is connected rigidly to one end of a spring 110, which has its opposite end secured rigidly to a collar 12 on the rod *s*.

A pin 9 is provided for the purpose of securing the sleeve 8 rigidly to the rod *s* when required. When this pin is removed, the two springs *t* and 110 are operative and form jointly a connection between the rods *s* and *s'*. When, however, the pin is inserted, as shown, the spring 110 is rendered inactive, and the spring *t*, acting alone, serves as a more rigid or stiffer connection between the parts *s* and *s'*.

By properly locating the pins in the respective holes to limit the movement of the 130

aws and by adjusting the rod 10 to vary the distance between the jaws the machine may be adapted to handle matrix-lines of different lengths and to locate these lines at either end 5 or at the middle of the mold. In other words, the devices may be caused automatically to indent the type characters on the slug at either or both ends to any predetermined extent.

10 The pin *j* is set to limit the movement of the right-hand jaw *c* to the left when the mechanism is used to indent the slug at the right side. This pin is also set to limit the movement of the right-hand jaw *c* to the right 15 when it is required to indent on the left-hand side of the slug, and for this purpose it is used only in the hole at the extreme right.

It will be understood that in the operation 20 of the machine the jaws stand normally at the right in position to receive the composed line as it is lowered between them by the first elevator, as usual. Immediately after the line is delivered the cam and intermediate parts will move the jaw *c* to the left until it is arrested by the pin *j*. As the jaw *c* carries the matrix-line before it toward the left the matrices push the jaw *b* backward a corresponding 25 distance.

If justifying wedges or spacers are used in 30 the line, they will be actuated in the ordinary manner and will crowd the line out tightly between the two jaws, the separation of which will be limited by the bar *e* and rod 10, as before explained. When short matrix- 35 lines are employed, the spring *t* alone is used; but when long matrix-lines of the full length of the mold, or approximately so, are employed the pin *g* is removed, so that the connections may yield more readily to the greater 40 extent required.

It will be understood that the distance between the pin-holes and the relation of these pins to the mold is such that the jaws may be arrested with their ends overlapping the 45 mold for any predetermined number of ems. In this manner successive slugs may be cast with equal indentations, or, in other words, with blank surfaces of equal length to admit of printing cuts or electrotypes being laid 50 thereon or of their ends being severed to admit a cut or engraving into the font.

We believe ourselves to be the first to rigidly connect or couple together two matrix-confining jaws, both of which are movable 55 endwise while thus connected.

We also believe ourselves to be the first to combine with matrix-confining jaws means for moving them endwise in unison and the first to combine with a jaw a yielding mechanism 60 for moving the same and adjustable stop devices by which it may be arrested at different points, and also the first to combine with the two jaws movable endwise adjustable stop devices engaging the respective 65 jaws, and it will be manifest to the skilled

mechanic that the details of construction may be widely modified without changing the principle of action or passing beyond the scope of our invention.

Having described our invention, what we 70 claim is—

1. In a linotype-machine, a slotted mold wherein the linotype is formed, in combination with two jaws adapted to confine the matrix-line in operative relation to the mold, 75 said jaws rigidly connected and arranged to move in the same direction in unison; whereby the matrix-line, regardless of its length, may be confined in any required relation to the mold. 80

2. In a linotype-machine, two line-confining jaws adapted to move endwise in unison, in combination with a rigid connection adjustable in length; whereby the distance between the jaws may be varied. 85

3. In a linotype-machine, a slotted mold wherein the linotype is formed, in combination with two connected jaws adapted to confine the matrix-line in front of the mold and to move endwise in relation to the latter, and 90 means for automatically effecting the movement of said jaws simultaneously in the same direction; whereby the matrix-line, regardless of its length, may be set in any required relation to the mold. 95

4. In a linotype-machine, two connected matrix-confining jaws arranged to reciprocate in unison, in combination with a spring connection tending to move said jaws in one direction, and an adjustable stop to limit 100 their movement.

5. In a linotype-machine, two connected matrix-confining jaws arranged to move to and fro in unison, a spring connection tending to move said jaws in one direction, and 105 automatic mechanism for moving them in the reverse direction.

6. In a linotype-machine, two sliding matrix-confining jaws, a direct connection between said jaws, a spring tending to move 110 the jaws in one direction, an adjustable stop to limit their movement in the opposite direction, and automatic mechanism including a yielding spring to move the jaws toward said stop. 115

7. In a linotype-machine, the combination of a mold, matrix-confining jaws movable lengthwise of the mold, means for automatically lifting said jaws and adjustable stop devices to limit their movement in each direction. 120

8. In a linotype-machine, a slotted mold, a matrix-confining jaw movable lengthwise of the mold, a spring tending to move the jaw in one direction, an adjustable stop to limit 125 said movement, and means for automatically moving the jaw in the reverse direction.

9. In a linotype-machine, a mold, two matrix-confining jaws movable lengthwise of the mold, means for changing the distance 130

between the jaws that they may confine matrix-lines shorter than the mold, and automatic means for moving the jaws and the intermediate matrices simultaneously in one

5 direction; whereby the matrices may be located at the desired point in relation to the mold.

10. In a linotype-machine, the combination of a slotted mold, two matrix-confining jaws arranged to slide lengthwise of the mold and to close its front face, and an adjustable connection between said jaws; whereby they may be caused to move in unison and their separation limited.

15. 11. In combination with the sliding jaws *b* and *c*, a connecting-bar *e*, and means for changing the distance between the jaws.

12. In combination with the sliding jaws *b* and *c*, the bar *e*, and the longitudinally-adjustable rod 10.

13. In combination with the sliding jaw *c*, the cam *o*, intermediate connections for imparting motion from the cam to the jaw, and an adjustable stop to limit the movement of 25 the jaw.

14. In combination with the sliding jaws *b* and *c*, an adjustable connection between them, means for reciprocating the jaws, and two adjustable stops to limit the movement 30 of the respective jaws.

15. In a linotype-machine, in combination with the sliding jaws *b* and *c*, adjustable stops to arrest the movement of the respective jaws in an outward or backward direction.

35. 16. In a linotype-machine, in combination with the matrix-confining and mold-closing jaw *c*, having a lip or shoulder *c'*, a stop arranged to be set on the right or the left of said lip at will; whereby the movement of the jaw may be limited in either direction.

17. In combination with the sliding jaws *b* and *c*, the two series of holes, and the adjustable stop-pins adapted for insertion therein.

45 18. In a linotype-machine, the combination with a sliding jaw, a movable stop to limit its motion, an actuating-cam *o*, and the yielding connection between said cam and jaw.

50 19. In combination with the sliding jaw *c*, the lever *n*, a cam to actuate said lever, a yielding connection between the lever and jaw, and a spring acting in opposition to the cam to move the jaw in a reverse direction.

55 20. In combination with the sliding jaw *c*, the rack-bar *d* connected therewith, its actuating-pinion, a cam and lever, and a connection from the pinion to the lever.

60 21. In combination with the matrix-confining jaw *b*, the adjusting and supporting rod 10 adapted to engage a supporting-stud 4 at different points, and a spring to maintain the engagement, substantially as shown; whereby instantaneous disconnection and 65 adjustment of the rod is permitted.

66 22. In a linotype-machine, a slotted mold in combination with two matrix-confining jaws arranged to move simultaneously in the same direction lengthwise of the mold, and 70 means for maintaining the distance between the jaws; whereby they are adapted to present a matrix-line of given length opposite any required portion of the mold.

75 In testimony whereof we have signed our names to this specification in the presence of two subscribing witnesses.

ROBERT JOHN FOSTER.
HONORE LAUZON.
